UNITED STATES PATENT OFFICE.

HENRY TALICHET, OF AUSTIN, TEXAS.

PROCESS OF AND APPARATUS FOR REFRIGERATING CARS.

SPECIFICATION forming part of Letters Patent No. 308,008, dated November 11, 1884.

Application filed May 12, 1884. (No model.)

To all whom it may concern:

Be it known that I, HENRY TALICHET, of Austin, in the county of Travis and State of Texas, have invented certain new and useful 5 Improvements in Process of and Apparatus for Refrigeration, of which the following is a full, clear, and exact description.

My invention has for its object to provide an improved system of refrigeration and apparatus for applying the same to practical use.

The invention consists in a process and various sub-processes and apparatus whereby the passage of air-currents over a water-saturated porous jacket wholly or partly enveloping a chill-room is made rapidly to evaporate the water for cooling the chill-room, which has a surrounding air-space fitted with exhaust-fan ventilators for inducing rapid air-currents over the saturated jacket, and whereby also the chill-room is ventilated and pure atmospheric air supplied thereto in a dry condition, thus avoiding the presence of "dead air" in the chill-room, and whereby, also, the cold-water drip from the ice-chamber is utilized to cool the chill-room by its distribution over the exterior surfaces of the room, and the flow of the drip-water may be controlled at any desired predetermined temperature, the whole process and apparatus being extremely simple and well calculated for effective and economical refrigeration, all as hereinafter fully described and claimed.

My invention is applicable to almost every usual form of stationary refrigerator in cold store-houses, provision-houses, breweries, &c.; but in its application to refrigerating railway-cars an opportunity is afforded for combining all the important features of my invention in a manner clearly to set forth its advantages, and I will more particularly describe the invention as applied to a railway-car.

Reference is to be had to the accompanying drawings, forming a part of this specification, 45 in which similar letters of reference indicate corresponding parts in all the figures.

Figure 1 is a vertical longitudinal sectional elevation of a railway-car embodying my improvements. Fig. 2 is a plan view of the same in section on line $x'x'$, Fig. 1. Fig. 3 is

a vertical transverse section on line $y'y'$, Fig. 1. Fig. 4 is an enlarged sectional view of the head of one of the chill-chamber ventilating flues or pipes. Fig. 5 is a plan view of the tubular serpentine floor or tray of the ice-chambers, and which also forms a part of the chill-room ventilating apparatus; and Fig. 6 is an enlarged detail view of the electrical connection for opening the drip-cocks of the ice-chambers.

The letter a indicates the body of the car having any approved double or packed walls serving as non-conductors of heat and cold, and suitable side door or doors. The car in this instance is fitted with two chill-rooms, 65 b , one at or near each end, and of a size to afford free air-spaces c at the sides and ends of the rooms, the center air-space, d , being wider for access to the rooms through their doors e . These chill-rooms are jacketed on the sides and 70 top, if desired, with porous jackets h of unglazed earthenware, felt, or any other absorbent material. The chill-rooms rest upon open-work or slat floor f , beneath which I arrange a water tank or tanks, g , in which may be stored 75 water, or water and ice, or ice only, with the drippings of which the porous jackets of the chill-rooms are to be kept saturated by a pump, a' , located in the central air-space, d , and having suitable pipe-connections, b' , for discharging water from the tank g onto the top of the chill-rooms, to furnish a constant supply to the porous jackets by overflowing down the sides 80 of the jackets, to be absorbed and evaporated therefrom. The pump is to be geared with 85 one of the car-axles for being operated thereby by any approved contrivance of gearing, which it is not necessary to show. The tank g is to have a well consisting of a little depression, c' , into which the suction-pipe of the 90 pump will extend, and the bottom of the tank is to be made to descend each way to the well, for causing the water to flow thereto when low in the tank. The well should extend below the level of the bottom of the tank and under the 95 car, so far as space will allow, so as to drain off the drippings in case ice alone should be stored in the tank. Air is to be forced into the space between the top of the tank and the floor on which the chill-rooms rest by one or 100

more air fans or blowers, *i*, arranged to be driven from the car axle or wheels, or by other motor, and to supply air to and force it through the air-spaces *c*, for evaporating the water from the jackets by the air-currents, to lower the temperature of the chill-rooms. The water not evaporated flows back into the tank along the top, which descends to the opening *d*. As but little water escapes, a continuous supply of water to the tank is not needed.

To stimulate and increase the air-draft to ventilate the air-spaces surrounding the chill-rooms *b* and facilitate the evaporation, I provide the car with ventilating or exhaust fans at *j*, preferably at the roof, and these fans may alone induce sufficiently strong air-currents through air-spaces *c* to render the use of the blowers *i* unnecessary; but the blowers are a valuable auxiliary. When the car is not moving and the blowers *i* are inoperative, and should the outside air have little effect to revolve the exhaust-fans *j*, there would ensue a rise of temperature in the chill-rooms, and to guard against this I locate over the chill-rooms *b* the ice-chambers *k*, opening at or near their tops for supply of ice, and tight at the bottom to hold the drip-water from the ice. The ice-chambers have direct cooling effect on the roofs of the chill-rooms and on the air surrounding them. The consumption of ice will be small with the exhaust-fans at *j* in operation by wind-pressure, and when the blowers *i* are in action the ice waste will be reduced to a minimum.

It will be noticed that the arrangements of apparatus above described provide for a cooling of the chill-rooms in every exigency of travel and without recourse to independent motors—as small steam engines or gearing driven from the locomotive—and the car, being self-contained, may be readily switched about as required in making up trains.

To ventilate the chill-room *b*, I have arranged at or near the bottom of the ice-chamber *k* the central portion, *m*, of a continuous tube or pipe, said portion *m* having a zigzag or sinuous construction for a circuitous route of the air therethrough. Said portion *m* serves also as a rack on which to place the ice and hold it above the drip-water collecting at the bottom of chamber *k*. The pipe portion *m* is set in inclined position and has a branch, *m'*, passing outward and downward and opening to the outer air at *m*², and has another branch, *m*³, from the other end, which passes down into the chill-room, and ranges, preferably, along the roof to the opposite side or end of the room, down which it extends to near the chill-room floor, where it has an open mouth at *m*⁴, all as shown in Fig. 1. Fresh air entering the pipe at *m*² rises to and through its sinuous portion *m* in the ice-chamber, and in its passage through the pipe the air is deprived of its moisture by condensation of the latter on the inner walls of the pipe, and the air then descends through branch pipe *m*³ to escape at *m*⁴ in a pure, cool, and dry condi-

tion, best suited for purposes of ventilation. The incline of the worm *m* permits a self-discharge of the condensed vapors taken from the air at or from the inlet *m*², so that the vapor-condensing action of the pipe will always be unobstructed.

At a point preferably as far removed as may be from the cold-air outlet *m*⁴, I pass into the chill-room *b* one open end, *o'*, of a pipe, *o*, the other open end, *o''*, of which may open directly into the air-space surrounding the chill-room, but preferably into the case of one of the exhaust-fans at *j*. The pipe *o* thus acts constantly to exhaust, circulate, and charge the air of the chill-room, the air-supply to which is maintained by the pipe *m m' m*², as before explained, and consequently "dead air" in the chill-room and the well-known deleterious effects of such air on the stored goods are avoided.

To increase and quicken the cold-air circulation in the chill-room I fit a cap, *p*, by spider-arms *q*, Fig. 4, to the head or outlet *o'* of pipe *o*, to induce air-currents from the cold-air spaces surrounding the chill-room to intermingle and discharge with the air-currents through pipe *o* from the chill-room. I make further provision for reducing the temperature of the chill-room *b* by saturating its top and side walls with the cold-water drip of the ice-chamber *k*, which I prefer to accomplish automatically and at any premeditated temperature by an electrical contrivance acting on a valved outlet from the ice-chamber, as next described.

The letter *r* represents any suitable electrical-battery device, the poles of which connect by wires with an electro-magnet, *s*, positioned to have effect on an armature, *t*, which is attached to a crank-arm, *u*, rigidly connected with the plug of a valve or cock, *v*, communicating with the interior of the ice-chamber next its floor, and discharging into a shallow tray on the chill-room roof formed by narrow ledges, flanges, or rims *w*, fixed to the side edges of the car-roof, so that the water escaping from the ice-chamber *k* shall fill the tray and flow over the rims *w* down the chill-room sides for materially reducing the interior temperature of the chill-rooms, the drip-water passing below into the tank or receptacle *g*, to be utilized by the pumps in a manner before described.

Any approved plan or devices for effecting a uniform distribution of the ice drip-water over the exterior walls of the chill-rooms may be employed.

For completing the electric circuit to open valve *v* of the ice-tank at any predetermined temperature of the air-spaces surrounding the chill-rooms any approved devices may be used. In the example shown I arrange a mercury bulb and tube, *a*², connected in the circuit by a wire, *b*², leading to one side of a magnet, *s*, and in the mercury-tube I pass a contact rod or wire, *d*², which connects to one pole of the battery *r* at the upper end, and against the lower end of which rod *d*² the mercury may

rise to complete the circuit. The rod d^2 being vertically adjustable, it may be set at will to close the circuit at any desired temperature, 40° being preferred in practice. When 5 the circuit is broken by the fall of the mercury, the spring u' , Fig. 6, draws back the valve-arm u and closes the valve to prevent waste of the cold water in the ice-tank.

It will be understood that I do not limit 10 myself to any particular size or form of tank g beneath the chill-rooms, and the particular form of the sinuous ventilating-pipe at m may vary from that shown with good results.

Among the advantages of my invention may 15 be named the automatic action of the apparatus, and without the use of chemicals as refrigerating agents, except those indirectly employed in the battery r . There is no complicated machinery required, and which is so liable to derangement, and the simple fan-blower and exhaust-ventilators are readily accessible. The quantity of ice used is reduced to a minimum, as its effects are required only or principally when the other means fail by stoppage 25 of the car, and the small quantity of ice required to be carried increases the freight-car-rying capacity of the car. The chill-rooms are thoroughly ventilated, the water required is everywhere obtainable, and the cars may 30 be built and maintained at comparatively small cost.

Having thus fully described my invention, I claim as new and desire to secure by Letters Patent—

35 1. As an improvement in a process of refrigeration, passing atmospheric air-currents over a water-saturated jacket of porous material enveloping a chill-room positioned in a cold-air space, said chill-room having an adjacent or superposed ice-chamber, in which is placed in inclined position a sinuous induction ventilating-pipe having branches opening into the outer air and into the chill-room, substantially as specified.

45 2. As an improvement in a process of refrigeration, passing atmospheric air-currents over a water-saturated jacket of porous material enveloping a chill-room positioned in a cold-air space, said chill-room having an adjacent or superposed ice-chamber, in which is placed in inclined position a sinuous induction ventilating-pipe having branches opening into the outer air and into the chill-room, which latter also has an eduction ventilating- 55 pipe discharging into the outer air, substantially as specified.

3. As an improvement in a process of refrigeration, passing atmospheric air-currents over water-saturated jacket of porous material 60 enveloping a chill-room positioned in a cold-air space, and which room has the cold-water drip from its adjacent ice-chamber distributed over its exterior walls automatically by mechanism operated by variations of temperature, 65 substantially as specified.

4. The combination, in a refrigerating apparatus, of the inclosure a , chill-room b , resting upon an open floor, f , and located in a surrounding air-space, the porous jacket h , a water-reservoir, and connections for saturat- 70 ing the porous jacket, and an ice chamber, k , substantially as described.

5. The combination, in a refrigerating apparatus, of the inclosure a , chill-room b , having open floor f , porous jacket h , and a water-sup- 75 ply thereto, an ice-chamber, k , and an induction ventilating-pipe, $m m' m^3$, communicating with the outer air and with the interior of the chill-room, said pipe having a sinuous course through the ice-chamber, and an induction ven- 80 tilating-pipe, o , connecting the chill-room with the outside air, substantially as shown and de-scribed.

6. The combination, with the chill-room b and its ice-chamber k , of the induction venti-lating-pipe $m m' m^3$, opening to the outer air and chill-room and passing in a sinuous course through the ice-chamber and the eduction venti-lating-pipe o , connecting the chill-room with the air-inlet of a ventilating-fan, which ex-hausts the air from the space surrounding the 90 chill-rooms, substantially as shown and de-scribed.

7. The eduction ventilating-pipe o , leading from the chill-room b and to an opening from 95 the cold-air space to the outer air, said open-ing being fitted with an exhaust-fan ventilator, substantially as shown and described.

8. The eduction ventilating-pipe o , leading from the chill-room b and to an opening, j , 100 from the cold-air space surrounding the chill-room to the outer air, said opening being fit-ted with an exhaust-fan ventilator, and said pipe o having a cap, p , for stimulating induced outflowing air-currents, substantially as shown 105 and described.

9. The combination, with the chill-room b , the exterior ice-chamber, k , and its ice-water drip-valve v , of means for discharging the ice-drip water over the exterior walls of the chill-room, 110 substantially as shown and described.

10. The combination, with the chill-room b , the ice-chamber k , and its drip-water valve v , of a shallow tank on the roof of the chill-room, substantially as shown and described. 115

11. The combination, with the chill-room b , the ice-chamber k , its drip-water valve v , and means for discharging the drip-water over the exterior walls of the chill-room, of an electrical apparatus connected to open the drip-valve by 120 a completion of an electrical circuit caused by a rise of temperature, and arranged to effect a closure of the valve when the circuit is broken, substantially as described.
